JEAN J. GRAIN, OF NEW YORK, N. Y.

BEST AVAILABLE COPY

CONTROL AND PAY SYSTEM.

1,054,198.

Specification of Letters Patent. Patented Feb. 25, 1913.

Application filed October 6, 1909. Serial No. 521,326.

To all whom it may concern:

Be it known that I, JEAN J. GRAIN, a subject of the Emperor of Austria-Hungary, and a resident of New York, county 5 and State of New York, have invented certain new and useful Improvements in Control and Pay Systems, of which the following is a full, clear, and exact description.

This invention relates more particularly 10 to means for controlling pay checks and the like in hotels, restaurants and the like.

In the devices and systems ordinarily employed by the best hotels and restaurants to avoid loss due to the carelessness or dishonesty of waiters and other employees, the said 15 systems or devices are either too complicated or impracticable, and when the same can be used they do not serve properly the purpose for which they are intended, and 20 are also difficult to audit or control. The control of the individual checks is impossible under the ordinary system, and much time and labor is consumed in the ordinary means employed for checking as well as the 25 cost incident to the employment of checkers. The usual system requires some days in which to audit the accounts and receipts of the day where the business is large as is the case with the large hotels, so that it is im- 30 possible to tell for some time just what is the condition of business.

The primary object of the invention is to overcome the objections referred to and to provide a system and devices to do away 35 with the ordinary checkers and checking utensils, thus saving the expense resulting from such methods, and to dispense with a part of the help usually employed in the auditing department; and to provide a sys- 40 tem in which the waiter or waiters are absolutely controlled so that no loss by accident or otherwise can result from the carelessness or dishonesty on the part of the waiter without being detected, and at the same time 45 controlling and auditing each transaction so that the condition of business within a very short time can be known and any discrepancies immediately ascertained.

Other objects of the invention are to im- 50 prove the service, as the waiters do not have to wait to get the order checked by the checker, and the waiter is permitted to assist in putting the price on the checks, but which assistance of the waiter is absolutely 55 under control; to provide means whereby the use of checks out of their rotation and

the presenting of wrong checks to guests are prevented and also each check or book so controlled and the system so arranged that the waiter must return his check book 60 each day after business, so that the objections arising from leaving them in the pocket over night is avoided, and to provide a system which is substantially self-auditing, as the auditing may be immediately 65 transacted after the close of business by the same person who is intrusted with keeping score upon the system.

Another object of the invention is to provide means for the immediate review of the 70 individual checks, portions or coupons which form a part of a check, and which are employed in connection with the sale of goods other than such as are found in the dining room, as for example, those known 75 as appetizers, articles coming from the bar and cordials or cigars, and the easy control of the amount of these coupons used or not used.

A further object of the invention is to 80 readily determine how many waiters have worked, the numbers of checks they have used, the individual amount of coupons employed for the purchase of goods in other departments than the dining room, and the 85 easy detection of any error committed on the part of the employees through neglect or otherwise in the use of the coupons.

With these and other objects in view, the 90 invention will be hereinafter more particularly described with reference to the accompanying drawings, which form a part of this specification, and will then be pointed out in the claims at the end of the description. 95

In the drawings, Figure 1 is an elevation showing a book opened and containing one form of pay checks used by the waiter. Fig. 2 is a plan view, looking from the top of the book. Fig. 3 is a detail of one of the duplicate checks. Fig. 4 is a detail view of the controller's sheet. Fig. 5 is a detail view of the sheet for final report of the controller of each day's transaction. Fig. 6 is a detail view of one of the sheets of the cashier's 100 day book, used in connection with the waiter's check for controlling the same. Fig. 7 is a detail view of the cashier's final statement of the transactions for the day; and Fig. 8 is a detail view of a guide for 110 the sheets of the cashier's day book.

While I do not show all of the sheets em-

ployed in carrying out my system, it will be understood that the number of sheets of each kind and size of the same may vary, and that the said sheets or members employed as a part of the system may have the printed matter thereon changed to suit the particular use to which the invention is put.

The waiter's check 10, Fig. 1, may be arranged in the form of a pad or otherwise, 10 and may be held to the cover or backing 11 at the edges thereof, as at 12, and between every two original checks 10 is a duplicate check 13 on which are characters to indicate to which check the duplicate belongs, and 15 said duplicate and original may form part of a single sheet or of separate sheets as desired. Each original check 10, the numbers of which may run from one to one thousand or otherwise, has its body portions 20 14 provided with lines to divide the articles to be ordered and on opposite sides of the cover or backing are the cards or members 15 and 16, the former of which may represent the wine list with the prices thereon, 25 and the card or member 16 the menu for dinner or breakfast with the prices thereon, and each of these members or cards 15 and 16 may have horizontal lines spaced apart and corresponding to the position of the 30 horizontal lines of the original check. These cards 15 and 16 may be detachably held under clips or corner pieces 17 so that the same may be readily removed, and the cover may be made of such form that it may be folded over as in a book.

Each check 10 has a part or column 18 for the number or portions of the articles ordered, a part 19 for the articles, a part 20 for the price of the articles ordered, and a 40 duplicate part or stub 21 for the price of the articles ordered. The parts 18, 19 and 20 are substantially the same as the ordinary form of waiter's check but instead of the usual checker putting down the price and 45 the amount, it is intended that the waiter himself attend to this and the amount or total of the order is also filled in in the part 20 by the waiter. The waiter puts a carbon sheet between the original check 10 and the 50 duplicate thereof, as for example the one shown in Fig. 3, so that all insertions on the original check 10 appear also on its duplicate. Instead of the checker the controller himself, when the goods are ordered, compares the articles with the check and the 55 prices of the same as made by the waiter, and these prices if proper are also inserted in the part 21 for dollars and cents so that duplicate prices appear on each check, and 60 the amount of all the articles may be added by the controller himself or this operation may be left to the cashier. The parts 20 and 21 are divided by a line of perforations 22 and the body of the check is also per- 65 forated horizontally, as at 23, so that the

check portion may be separated from the body portion and leave the part 21 as a stub which remains as a part of the book and which stub has the price of the articles and total amount thereon to serve as a controlling means for the check portion when removed.

The duplicate check 13 is perforated lengthwise, as at 24, and horizontally, as at 25, corresponding to the perforated lines 22 and 23 so that the duplicate part or check portion may be removed from the check book and sent to the kitchen so that the order may be filled which is often complicated and requires some time to fill. The proper checking and controlling of the order can be done while the order is being filled and the order when filled in this way is not likely to become cold as is often the case in places doing a large business employing a number of waiters where one waiter has to wait for the others to have the checker properly stamp the price of the articles on the body of the check to correspond with the order filled. The original 80 check 10 is also provided with a stub 26 which may be readily divided from the body portion by means of the perforated or marked lines 27, and this stub is intended to be retained by the waiter, after the amount 90 of the order has been paid, in order that the waiter may have a record of the amount paid by him on each check. After the order has been filled and the amount of the order has been submitted to the guest, the waiter 100 delivers the original check removed from the book or still in the book to the cashier to be removed by the cashier who totals the amount of the order on the controller's stub 21 and enters the amount which should correspond with that added by the waiter. The cashier also enters the amount on the waiter's stub 26 and marks the same paid and delivers the same to be retained by the waiter. The book is then returned to the 110 waiter for a further order and should a deduction have to be made, as for example one item should not correspond with the order, then such deduction from the total amount is entered in the part 28. The stub 21 and the duplicate stub serve to control the check made out by the waiter, and the amount entered on the waiter's stub serves as a controlling means for the cashier.

The body of the original waiter's check is 120 provided with a plurality of coupons 29, 30, 31 and 32. The coupon 32 remains as a part of the stub 21 and similar checks or coupons form a part of the duplicate check. Each coupon has the number of the waiter and the 125 number of the check, and the coupons to be used, that is 29, 30 and 31 have also a character to indicate the department for the item or goods to be purchased. The coupon 29 has the letter A for appetizer, such as cock- 130

tails; coupon 30, the letter B, for purchase at the bar, as for example champagne and other wines and liquors; and the coupon 31 has the letter C for cigars and cordials or other articles. If either of the coupons 29 to 31 are to be used, as for example coupons 29 and 30, the price of the order is placed upon the coupon, which will be also indicated on the duplicate coupon, and the specific order with its price is entered so as to form a part of the check, and this amount entered by the waiter is verified on the stub 29 by the controller as the waiter leaves the department where the items are to be had. 15 Any order such as should ordinarily go on the coupon 31, instead of tearing off the other two coupons, the controller may change the lettering on the coupon accordingly so that the outer coupon would answer 20 for any one of the purposes for which the other coupons are used, and a similar change would be indicated on the duplicate coupon, thus avoiding the necessity for removing any more coupons than is necessary to supply 25 the order given. By this means the controller determines whether or not the waiter has supplied the proper items, and also that the price given is correct, and the said entries may serve to control each other in such 30 a way that any mistake would be quickly ascertained.

It is desirable that the controller have some record of the checks and coupons and for this purpose the controller has a sheet 35 or check 33 which is divided horizontally, as at 33^a, to correspond with the number of waiters and vertically into a plurality of parts 34 to correspond with the number of checks, the sheet being of any suitable size 40 to adapt the same for use in connection with any desired number of checks and there being as many of these as desired. Each part 34 is sub-divided into a plurality of divisions, as for example, 35, 36, 37 and 38, the first row 35 for all of the waiters has the letter A means appetizers; the second the letter B representing coupons for the bar; the third the letter C for cigars or cordials, and the row 38 the letter F for food. As will be 45 seen only two of the coupons have been used by the waiter and these are indicated under letters A and B, and one check for food has been used, the same would occur with any number of checks used, and the total should 50 be added at the bottom. If any of the coupons are missing, the controller can enter on any space the letter *m*, or if any of the coupons are void can indicate the same by the letter *v*, so that a complete record is obtained immediately 55 the checks are used, void or missing. The controller's sheet 33 is intended as a record of the transactions for the entire day with the different waiters, and this record is summarized in the final report sheet or member 60 32, as shown in Fig. 5. This sheet or

member 39 is provided at one edge, as 40, with the letters A, B, C, and F, the first three indicating the coupons and the last the food check, and under these letters are added all of the coupons and checks of all of the 70 waiters. The member 39 is divided at 41 to give the total number of food checks used, those missing or those void, and the total is placed to one side as indicated, which, as before stated, represents the transaction of 75 one check and its coupons for one waiter while the total for a number of waiters would be correspondingly larger. There is also a place, as at 42, for any special remarks with relation to any waiter or waiters, 80 and a part 43 is provided for the coupons indicating those used, blank, missing or void, together with any remarks, as in the space 44, relating to the same. These totals can be had very readily from the controller's sheet 85 by adding the respective columns of each check under the letters A, B, C, and F, and this can be done in a comparatively short time so that the final report of the controller can be made shortly after the closing of business, in order that the entire day's transaction may be known. These members or sheets not only serve as controlling means in case any discrepancy arises, but the sheet 33 also serves to control all of the checks and 90 the coupons of all of the waiters, and the coupons delivered by the waiters to the departments to remove the items therefrom, and in this way any error by oversight, or otherwise, will be quickly discovered. 95

When the waiter has submitted the check to the guest and receives the money to pay the cashier, the cashier after the payment of the same and the removal of the waiter's stub delivers it to the waiter and enters 100 upon a sheet or member 45 the amount of the check. These cashier sheets or checks 45, Fig. 6, may correspond in number with each waiter and the number of these sheets may correspond to the number of checks the 105 waiter is expected to use. These sheets 45 may be each provided with openings, as 46, so that they may be loosely held in substantially the same manner as in loose-sheet systems, and each sheet may be cut away at one 110 side to provide a tab 47 on which may be placed a character indicating the number of the waiter. The sheets for each waiter have a similar tab and these tabs are so arranged that they will follow in succession. 115 As shown, the sheet or member 45 is arranged for thirty-five (35) checks of waiter No. 1, and the amount of each check as the waiter submits the same to the cashier properly verified, is entered under the column 47^a marked cash and in a line corresponding to the number of the check. In case of hotels some checks are not paid immediately, and in this case, a column 48 is provided for the name of the guest, the column 49 for the 120 125 name of the waiter, and the column 50 for the 130

room, and the column 50 for the amount charged. There is a column 51 for liquors, etc., a column 52 for the food and a column 53 for cigars, so that the cashier can quickly and easily enter up the total amount taken in by each waiter during the day, and these amounts must correspond to the stubs in the books which are returned to the controller's office each day and also with the checks as paid to the cashier, and the said sheet or member 45 serves as a means to quickly ascertain any misuse of the checks, or using the same out of rotation, and serves also to control in a measure the controller's sheet, as well as the latter acting to control the sheet or sheets of the cashier.

The sheets or members 45 may be arranged in the form of a book and to avoid the liability of a mistake in entering up the amount on the sheet of the wrong waiter, a guide 54 is provided which has the numbers of the waiters on the body thereof, and this guide has a part 55 which is adapted to enter a recess or cut-away part 56 of the sheet or member 45 and is adapted to cover up the tabs 47 of all of the sheets except of the particular waiter against which the entries are to be made. If it is waiter No. 1 the said guide 54 will cover all of the tabs of the waiter's sheets except waiter No. 1 for example and these tabs will correspond to the position of the waiter's numbers on the guide, so that if one on the guide is covered it will be seen that the entries are to be made opposite this number, though the guide may be used in any other desired way.

A final statement is to be delivered by the cashier after each day's transactions to the controller, as the number of sheets 45 will vary according to the number of waiters and the number of checks used each day. This sheet or member 57, Fig. 7, is divided into a column 58 with the number of waiters which are likely to be employed during the day, and a column 59 for the amount of cash received by each waiter, and at the bottom of the column the total of cash received during the day. A second column 60 is provided to represent the number of checks cashed; a column 61 for the amount charged and a column 62 for the number of checks charged. This final sheet can be quickly filled out after the close of business, so that the exact amount of cash received and amount charged to guests and the number of checks cashed or charged can be quickly determined. These totals should correspond with those of the controller's sheet so that each transaction of the different sheets is readily apparent, and the controller's sheet serves to immediately determine if any mistake has been made on the part of the cashier, and each serve to control the other, and the waiters as well as the food and other items from the several departments.

In the drawings, the transaction of one waiter for one check only is shown but this will serve to illustrate the entire system for a number of waiters, and it is only necessary in addition to take into account such checks as are void, missing or blank.

From the foregoing it will be seen that a simple and efficient system is provided for absolutely controlling the waiters; that said system and devices, forming a part thereof, do away with the usual checkers and the expense and delay connected therewith; that each transaction is controlled and audited and that the final report of the day's business may be readily made within a very short time after the close of business; that the various devices serve to control each other so that any inaccuracy or error will be quickly ascertained; that a simple and effective check with coupons is provided; that a simple and efficient book of checks for the use of the waiters is provided in which cards representing the wine or menu may be readily held for the purpose of avoiding mistakes on the part of the waiter; and that any mistake or error on the part of the waiter or of any of the other departments will be quickly discovered as the several departments by the devices serve to control each other.

Having thus described my invention, I claim as new and desire to secure by Letters Patent:—

1. The combination with a cover, of a plurality of sheets held to said cover and each sheet arranged in pairs, one of which is adapted to form a duplicate, each sheet and its duplicate being numbered and provided with a check portion for the entry of the articles ordered and the amount of same, a stub portion permanently held to the cover and adapted for an entry of the amount of the articles ordered to correspond with the check portion, a plurality of coupons each numbered identically with the number of the check portion and differently marked to represent orders from different departments, and a detachable stub for the waiter forming a part of the original sheet of each pair, the said check being arranged for the entry of any deductions from the amount of check.

2. A pay check for waiters comprising a sheet provided with duplicate columns for the entry of the cost of articles, spaces for the articles ordered; and a column for the entry of the portions of orders, the cost columns being separated by a vertical line of perforations and said line of perforations being intersected at the top and bottom by longitudinal lines of perforations, said longitudinal and vertical perforations forming a detachable check portion, said sheet having a waiter's stub below the lower line of perforations, the body portions of the check

and stub bearing identical marks of identification, said sheet having its upper portion provided with spaced parallel lines of horizontal perforations forming detachable 5 coupons for the entry of articles from different departments than the detachable check.

This specification signed and witnessed this 4th day of October A. D. 1909.
